UNITED STATES PATENT OFFICE.

ERICK L. HALL, OF INDIANAPOLIS, INDIANA.

FLOORING JACK.

Application filed November 10, 1921. Serial No. 514,286.

To all whom it may concern:

Be it known that I, ERICK L. HALL, a citizen of the United States, residing at Indianapolis, in the county of Marion, State 5 of Indiana, have invented a new and useful Flooring Jack; and I do hereby declare the following to be a full, clear, and exact description of the invention, such as will enable others skilled in the art to which it 10 appertains to make and use the same.

The invention relates to floor jacks and has for its object to provide a device of this character comprising a U-shaped member adapted to be clamped to a joist, a rack longitudinally movable in said clamping member above the joist and provided with a plank engaging element, said rack being longitudinally movable by a segmentally shaped lever carried gear. Also to provide means 15 for holding the lever and gear in various positions.

A further object is to provide adjustable blocks carried by threaded shafts extending rearwardly from the board engaging member, said blocks forming means whereby boards may be jacked and held when it is impossible to use the board engaging member.

A further object is to provide the board 20 engaging element with a transverse slot for the reception of the tongue of a floor board and with a cutaway portion allowing a flooring nail to be driven into the board adjacent its tongue and into the joist beneath the 25 board.

With the above and other objects in view the invention resides in the combination and arrangement of parts as hereinafter set forth, shown in the drawings, described and 30 claimed, it being understood that changes in the precise embodiment of the invention may be made within the scope of what is claimed without departing from the spirit of the invention.

45 In the drawings:—

Figure 1 is a side elevation of the floor jack showing the same in position for use.

Figure 2 is a top plan view of the floor jack.

50 Figure 3 is a vertical sectional view through the floor jack taken on line 3—3 of Figure 1.

Referring to the drawings, the numeral 1 designates a base, which base is U-shaped in 55 transverse cross section and rests on the upper side of the joist 2. Base 1 has its

flanges 3 and 4 downwardly disposed and the flange 4 provided with sharpened lugs 5 which are forced into one face of a joist 2 by means of a pivoted cam 6 which engages 60 the opposite side of the joist 2. It will be seen that the base 1 may be easily and quickly clamped on the joist 2 for rigidly holding the device as a whole during a floor board jacking operation. Extending upwardly from the base 1 are spaced flanges 7 and 8, between which flanges is pivotally mounted on a pin 9 an operating lever 10. The lower end of the lever below the pivotal pin 9 is provided with segmentally disposed 70 gear teeth 11 which mesh with gear teeth 12 in a horizontally disposed rack bar 13, which rack bar is longitudinally movable according to the direction of movement of the lever 10. The rack bar 13 is slidably 75 mounted in guides 14 of the flanges 7 and 8, therefore it will be seen that during the oscillation of the operating lever 10 that the rack bar 13 will also operate. The forward end 15 of the rack bar is provided with a 80 transversely disposed board engaging member 16 which is provided with a transversely disposed groove 17 which receives the tongue 18 of the flooring board 19, therefore it will be seen that when the rack bar 15 and the 85 members 16 are forced in the direction of the arrow a, the board 19 will be forced into close and binding engagement with an adjacent board, and if so desired held in said position by means of the pivoted dog 20 90 which cooperates with the ratchet teeth 21 carried by the flange 8. By providing holding means for holding the bar 15 against rearward movement, it will be seen that a board may be held at one point adjacent a 95 joist and that the operator may drive nails angularly through the board adjacent the tongue 18, thereby securing the board to the joist. The transversely disposed member 16 is provided with a cutaway portion 22, which 100 is in communication with the transversely disposed groove 17 and which allows a nail 23 to be driven into the board 19 adjacent the tongue 18 and into the joist 2 on which the device is secured, thereby allowing the 105 board to be secured to every joist. The pivoted dog 20 has connected thereto a connecting rod 24, which rod has its upper end connected at 25 to a pivoted finger engaging member 26, by means of which finger engaging member the pivoted dog 20 may be 110 controlled, however a coiled spring 27 is

interposed between the finger engaging member 26 and the lever 10, at a point above the pivotal point of the finger engaging member 26 and forms means whereby the pivoted dog 5 is maintained in engagement with the ratchet teeth 21 during a rearward movement of the lever 10, thereby holding the lever against forward movement immediately upon release of the finger engaging 10 member 26.

Pivottally connected at 28 adjacent the outer ends of the transversely disposed members 16 are rearwardly extending threaded shafts 29, which shafts have threaded there- 15 on blocks 30 which may be screwed onto the shafts 29 to various positions, and utilized for pulling the boards into place when the boards are too close together to apply the device to the upper side of a joist. When 20 the blocks 30 are utilized the device is disposed on top of the flooring and the tongue 18 of the board is received in the transversely disposed grooves 32 adjacent the lower ends of the blocks. Threaded shafts 25 29 may be detached when not needed by simply removing the cotter pins 33, which extend through apertures in the upwardly extending angular portions 34 carried by the threaded shaft 29.

30 From the above it will be seen that a floor jack is provided, which jack is simple in

construction the parts reduced to a minimum and the device compact thereby providing a jack which may be easily handled and moved from place to place.

35

The invention having been set forth what is claimed as new and useful is:—

A floor jack comprising a U-shaped base, clamping means for clamping said U-shaped base to a support, a rack bar slidably mounted in said base, a board engaging member carried by one end of said rack bar and located at one side of the jack, a lever pivoted in the clamping member, arcuately arranged gear teeth carried by said lever 40 and meshing with the rack bar and rearwardly extending threaded shafts pivoted to the board engaging member adjacent its outer ends and movable in a horizontal plane, said threaded shafts having threaded there- 45 on board engaging blocks having transversely disposed grooves therein and located at the opposite side of the jack from the first mentioned board engaging member.

In testimony whereof I have signed my 55 name to this specification in the presence of two subscribing witnesses.

ERICK L. HALL.
